UNITED STATES PATENT OFFICE.

MAX WINKLER, OF RIDGEWOOD, NEW YORK.

CONTAINER AND COVER ATTACHMENT.

1,233,632.

Specification of Letters Patent.

Patented July 17, 1917.

Application filed November 13, 1916. Serial No. 131,002.

To all whom it may concern:

Be it known that I, MAX WINKLER, a citizen of the United States, resident of Ridgewood, county of Queens, and State of New York, have invented certain new and useful Improvements in Containers and Cover Attachments, of which the following is a specification.

This invention relates to improvements in containers, and particularly to types of receptacles adapted to receive collections of ashes, garbage, rubbish and the like.

The principal object of the invention is to provide a can in which the cover is at all times positively engaged therewith so that the same may not become loosened and therefore subject to theft or loss.

A further object is to provide a can in which the cover may be readily secured over the top thereof or when it is desired to make use of the can, the cover may be held in close proximity to the outer side walls, thereby occupying substantially no extra space, and a third object is to provide such articles of a novel and pleasing design having ample strength, and which are well designed to receive material or discharge the same.

These and other like objects are attained by the novel design, construction, and combination of parts hereafter described and shown in the accompanying drawings, forming a material part of this specification, and in which:—

Figure 1 is a front elevational view of a container made in accordance with the invention.

Fig. 2 is a side elevational view of the same, the cover being shown disposed over the top of the can.

Fig. 3 is a transverse sectional view taken on line 3—3 of Fig. 1.

Fig. 4 is a vertical sectional view taken through the can, the cover being shown as engaged at the side of the can.

Fig. 5 is a similar sectional view showing the cover in a partially raised condition, and

Fig. 6 is a fragmental perspective view of the cover.

Like other containers of this class, the side walls of the can are preferably comprised of relatively strong metal plates oxidized or galvanized to prevent corrosion by the elements or contents, the walls being

formed with a base 11, the top 12 of the can, which is obviously cylindrical, being formed in a peculiar manner so as to present sides having a semicircular profile, the radius of the curve being substantially equal to that of the can, the material at the extreme front 14 and rear being extended slightly above the ordinary height of such receptacles.

In order to stiffen the vessel, a plurality of vertical strips 15 are secured to the outer walls, the lower end of the strips being engaged with the base band 16, and further held in position by a plurality of circumferentially disposed bands 18, rivets 19 being used at the intersection of the bands and strips the rivets passing through the receptacle, if desired, so as to bind the strengthening elements to the can.

At the rear or back side of the can, the bands 18 are carried outward as are also the vertical strips 15, forming a space 20, open at the top and suited to receive the cover 22, which is curved to a radius substantially equivalent to that of the side walls, the cover being held closely adjacent to the walls by reason of the bands and strips, as indicated best in Figs. 4 and 5.

In order to prevent separation of the cover plate 22 from the can, a rod or bar 23 is attached at its lower end to a plate 24 formed at the bottom of a pocket or recess 25, the recess being rolled or pressed directly into the material forming the can walls, at the rear thereof, as best shown in Fig. 3.

The upper end of the rod 23 is turned angularly as at 26 and secured directly to the wall 10 at the center of the recess 25, near the top of the can. Formed with the cover 22, is a lug 30 having an angular extension 31, suited to be received within the recess 25, the lug 30 having an opening 32 slidably engaged with the rod 23 in such manner that the cover may be raised from a normal horizontal position to one substantially vertical and allowed to slide down alongside the walls of the can, being guided by the opening 32, by means of which the cover is held in positive engagement and cannot be removed without disruption of the parts.

Upon opposite sides, near the front of the can, two of the vertical bars 15 are extended above the normal surface 12, the extensions 35 being receivable in appropriate openings 36 formed through the cover plate 110

so that when positioned over the top of the can it is held against lateral motion.

The cover is further provided with a link 38, attached to a lug 39, formed at its extreme front end, the link being engageable with an extending hook element 40 rigidly secured to the extreme front upper portion of the can. Thus, when the link is engaged with the hook, the cover is tightly held downward by means thereof in addition to the engagement of the opening 32, with the end 26 of the bar, and further prevented from moving sidewise by reason of the projections 35 being engaged within the openings 36.

When it is desired to open the can, the link 38 is pulled outwardly from the hook 40, the cover raised and allowed to slide downward in the space 20, where it is held in intimate relation to the walls of the can by reason of the bands and strips as shown, and prevented from movement by engaging the link 38 with a hook 42 formed outwardly on the end of the rearmost vertical bar 15, so as to permit of reversing the can in dumping its contents without releasing the cover from the side of the can.

Having thus described my invention, what I claim as new, and desire to secure by Letters Patent, is:—

1. In a container of the class described, the combination with a cylindrical can having concave top edges formed transversely of the walls, a curved cover suited thereto, means for engaging said cover with the can, means receptive of said cover formed with

the rear walls of the can, and means for securing said cover in said receptive means.

2. In a container of the class described, the combination with a cylindrical body having a closed bottom, the walls of said body being formed with an arcuate profile extending transversely across, a cover suited to the top of said body, a rod secured at both ends in a recess formed in said body, means formed with said cover engageable with said rod, projections extending upward from the upper edge of said body adapted to engage with openings formed in said cover, means for securing said cover to the front of said can, and means receptive of said cover formed at the rear of said can.

3. In a container of the class described, the combination with a cylindrical body having an imperforate base, the upper edge of said body being curved in its profile, a curved cover suited to the top of said body, a plurality of vertical bars reinforcing said body, a plurality of bands encircling said bars and said body, means formed with certain of said bars, engageable with openings in said cover, a vertical rod secured in a recess formed in the rear of said body, means formed with said cover engageable with said rod whereby it is held against separation, and means formed with certain of said vertical bars and said bands receptive of said cover when disposed adjacent to the body walls.

In testimony whereof I have affixed my signature this second day of November, 1916.

MAX WINKLER.
